UNITED STATES PATENT OFFICE.

WILHELM SCHMIDT, OF WILHELMSHÖHE, NEAR CASSEL, GERMANY.

BOILER WITH SUPERHEATING-TUBES.

No. 823,551.

Specification of Letters Patent.

Patented June 19, 1906.

Application filed January 3, 1905. Serial No. 239,481.

To all whom it may concern:

Be it known that I, WILHELM SCHMIDT, a subject of the King of Prussia, German Emperor, and a resident of Wilhelmshöhe, near 5 Cassel, in the Province of Hesse-Nassau, German Empire, have invented certain new and useful Improvements in Locomotive Tube-Boilers with Superheating-Tubes, of which the following is an exact specification.

10 The improvements hereinafter described, with reference to several forms shown in the drawings, comprise a further development of the invention described in my United States Letters Patent No. 703,482, July 1, 1902, and have the object to remove certain defects or inconveniences still remaining, especially relating to the putting together and the taking apart of the apparatus.

In order to effect the easy removal and insertion of the superheating-pipes arranged in the enlarged smoke-tubes of the locomotive-boiler and forming an outward and return steam-conduit, it is desirable to increase the access to the connection between the superheating-pipe and the two steam-chambers for steam-inlet and steam-outlet, respectively. This led to the idea of still further extending the bend described in the aforesaid patent specification for enabling free access to the 25 tubes, so that now the bend is continued into a return-bend of the superheating-pipe which terminates in the direction of the smoke-box tube-plate, wherein the tubes are fixed. By this means the ends of the superheating-pipes 30 are kept clear of each other. They terminate in the upright or upwardly-sloping cover of the steam chamber or casing and can consequently be conveniently separately fixed and disconnected. This is obviously important in the working of a locomotive-boiler, because it is then an easy matter, by undoing 35 the means for fastening through the smoke-box door, to remove quickly one or other of the superheater elements, if defective, and replace it by a new one. The joints can also 40 be examined in each element or the leaks remedied, and that either during running or at a station.

The two characteristic features of this invention are the continuing of the bend of the superheating-pipes into the return direction and the fixing of same in an upright or upwardly-slanting cover of the steam casing or chamber.

Figure 1 is a longitudinal section of a 55 steam-boiler provided with the arrangement according to my invention. Fig. 1^a is a longitudinal section of a modified arrangement. Fig. 2 is a front elevation of the boiler according to Fig. 1. Figs. 2^a, 3, and 3^a are perspective views of the superheating-tubes. Fig. 4 is a perspective view of a superheater-tube arranged in one flue-tube. Fig. 5 is a front view according to Fig. 6. Fig. 6^a is a longitudinal section of a tube-boiler provided with a modified arrangement of my steam-superheater. Fig. 6^b is a front view of the boiler according to Fig. 6^a. Fig. 6 is a longitudinal section of a part of the steam-chest and several flue-tubes in a large scale. Fig. 6^c is an upper view of a superheater element according to Fig. 6^a. Fig. 6^d is a detail of the steam-chest according to Fig. 6 in a longitudinal section. Fig. 7^a is a longitudinal section of a boiler provided with a further 75 modified arrangement of my steam-superheater. Fig. 7^b is a front view according to Fig. 7^a. Fig. 7 is a longitudinal section of the superheater according to Fig. 7^a in a large 80 scale. Fig. 7^c is a modified constructional form, partially in a longitudinal section and partially in side elevation, showing a steam-chest having an inclined front wall. Figs. 8 and 8^a are front views of the superheater-tubes according to Fig. 7. Fig. 9 is a longitudinal section of a superheater part, showing another constructional form. Fig. 9^a is a front view according to Fig. 9. Fig. 9^b is a horizontal section of the steam-chest according to Fig. 9.

Fig. 1 and Fig. 2 of the drawings are longitudinal section and front elevation, respectively, of the simplest arrangement applied to a steam-boiler. *k* is the shell of the locomotive-boiler, and *v* the smoke-box tube-plate, in which the superheating-pipes are fixed steam-tight. The tubes in the top row are of enlarged diameter and contain the superheating-pipes forming outward and return steam-passages, as described in the aforesaid patent specification. *h* is the outward conduit; *r*, the return-conduit for the steam. Their end bends *h'* and *r'* are now, as also clearly shown in Fig. 2^a, bent back in the direction of the tube-plate *v* and terminate in the vertical flange *p*, parallel with the plate *v*, the said flange being fixed to the cover of the two steam-collectors *p'* and *q'*, Fig. 7. The su-

perheating-pipes are thus not secured directly to the said cover, but to a flange p , which in turn is fixed to the cover by one or two screw-studs therein, the nuts m thereon serving to tighten the flange p on the return-bends h^2 and r^2 to the cover of the steam-chambers. A copper ring may be inserted between them for making tight joint. It will be seen that the tightening-nuts m are clear of obstruction and separately accessible from the smoke-box door, so that they can easily be undone or tightened up.

As a modification the superheating-pipes h' and r' in Fig. 3 are shown to be somewhat looped or deflected from the straight line.

Fig. 3^a shows a modification in perspective view in which the superheating-pipes arranged in two smoke-pipes, one under the other, are fastened in series with one another. By this it is possible for the said pipes to be fastened in only one fixing-flange p , thereby reducing the depth of the steam-collectors. This reduction of depth in the construction is of great importance, as the space in the upper part of the smoke-box is very limited, the lower part of same being occupied by the boiler-tubes. In order to be able to place several superheater elements under each other, it is highly necessary to endeavor to reduce the height of the flange connection. Moreover, by means of this connection, in which the pipes are one behind the other, the number of the fixing parts will also be reduced, and therefore the working and construction simplified, which is also of great importance. Fig. 4 shows another construction of a single element, in which only one nut is required to fasten the cover-plate p to the steam-casing. Further, there are described two pairs of superheating-pipes situated in one tube. The steam passes through the pipe h' , situated in the large pipe s' , turns at h^5 at the rear, and then passes through the pipe r^3 toward the smoke-box tube-plate. After the pipe leaves the large tube it is preferable to bend it, as shown at r^4 , so that the superheating-pipe has an enlarged loop r^4 . It then again enters the enlarged pipe at r^6 , turns at r^7 , and returns again toward the smoke-box tube-plate h^6 . The pipe is there again bent a little outward, as shown in Fig. 5 at h^8 , and is then taken directly upward, as at h^9 , and terminates in the cover-plate p at r^2 , being given the rearward bend h^2 , which is a characteristic feature of the present invention. Fig. 5 shows this arrangement of the elements in front elevation, three single elements being situated in line with one another and partly covering each other. Fig. 6 is a longitudinal section of the same.

Fig. 5 shows that the pipes h^2 and r^2 , which start from and end at the plate p , are situated at a certain distance from each other, which distance is greater than the distance between the superheating-pipes in the large

tubes of the boiler, the separation being such that a nut can be fixed midway between the two pipes, and by this means to reduce the number of fixing parts. By the arrangement of pipes as above described, with fixing-bolts between, the fixing-bolts are not only accessible, but the enlarged pipes are not obstructed, so that they may be easily cleaned.

As is customary and as indicated in Figs. 5 and 6, not one series only of steam superheating elements but several, are employed in locomotive-boilers, and as there is only a relatively small space in the upper part of the smoke-box tube-plate it is necessary to arrange, when the number of the superheating elements is increased, that the vertical cover-plates p , in which the rearwardly-bent ends h^2 and r^2 of the superheating-pipes terminate, take up as little space as possible. Formerly it was not known how to save space in this respect, and it was necessary to make the connections in a horizontal plate, by which easy access was difficult. Constructions, by way of example, are shown in two modifications in Fig. 7 in longitudinal section and in Fig. 8 in front elevation. The characteristic feature of the arrangement is the connection one behind the other or in series, and particularly the special form of the superheating-pipes. In Fig. 7 the superheated steam is collected in the box p' and goes through the rearwardly-bent pipes h^2 first into the upper enlarged pipe I. The pipe h terminates in the rear of the chamber q , from which the pipe r starts. This pipe r is bent at r^8 to a large curve in order to enter the enlarged pipe II underneath. A similar turn takes place in the cap connection q^2 , and the steam goes through the return-pipe r and enters the upper steam-receiving casing q' through the bent pipe r' and the rearward bend r^2 . Here also are two enlarged pipes I and II, connected one behind the other or in series. The method of leading the steam through the element arranged partly behind the one just described is similar to that already described for the pipes I and II, but is in some respects different. The steam leaves p' , passes through the lower pipe h^2 , through the bent pipe h' , into the large pipe s' , leaves again at o' , then passes through the bend o^2 into the upper steam-pipe s' at o^3 , leaves again at o^4 , and arrives at the lower steam-box q' by way of r^2 . Attention is drawn to Figs. 7 and 8 to the peculiar method of tightly fixing the tubes in the upright walls of the casings p' and q' . As seen in Fig. 8, one series of perpendicular superheating-pipes leads at the upper end into the lower connection-plate p , while the other series of superheating-pipes is carried, by means of looping or deflecting from the straight line, into the upper connection-plate p . By this looping or deflecting, which may also be performed as shown in Fig. 8^a, a completely-unobstructed position

for the fixing devices is attained and the depth of the front plate of the steam-chamber is reduced as far as possible.

In Fig. 9 another modification is illustrated in a longitudinal section. Fig. 9^a is a front view of the same modification.

Fig. 9^b is a detail of the steam-chest. As clearly to be seen, one set of superheating-tubes is arranged in each enlarged smoke-tube, and two sets of superheating-tubes are brought in connection, so that the steam to become superheated passes first through the first set of superheating-tubes and then through the second set, after which it returns to the steam-chamber *q*.

The tubes of every set of superheating-tubes are arranged horizontally one to another, so that the lowest part of the enlarged smoke-tube is free of the superheating-tubes, by which arrangement the enlarged smoke-tubes can be easily cleaned.

The manner of the connection of the superheating-tubes one with another is easily to be seen from the drawings. By the arrangement of only one set of superheating-tubes in the enlarged smoke-tubes it is possible to reduce the diameter of the enlarged smoke-tubes to the utmost, and thereby to gain room for a sufficient number of not enlarged smoke-tubes *s* in the front plate of the smoke-box.

Having thus fully described the nature of my invention, what I desire to secure by Letters Patent of the United States is—

35 1. A boiler, with superheating-tubes, arranged in some enlarged smoke-tubes of the boiler, the ends of the superheating-pipes being bent backward in such a manner that they are turned backward into the direction 40 of the tube-plate of the smoke-box.

45 2. A boiler, with superheating-tubes, arranged in some enlarged smoke-tubes of the boiler, the ends of the superheating-pipes being bent backward in such a manner that they are turned backward into the direction 50 of the tube-plate of the smoke-box, the single superheating-tubes consisting of an outward and return steam-passage arranged in an enlarged smoke-tube of the boiler.

55 3. A boiler, with superheating-tubes, arranged in some enlarged smoke-tubes of the boiler, the ends of the superheating-pipes being bent backward in such a manner that they are turned backward into the direction 60 of the tube-plate of the smoke-box, the single superheating-tubes consisting of several outward and return steam-passages arranged in an enlarged smoke-tube of the boiler.

65 4. A boiler, with superheating-tubes, arranged in some enlarged smoke-tubes of the boiler, the ends of the superheating-pipes being bent backward in such a manner that they are turned backward into the direction 70 of the tube-plate of the smoke-box, the ends of the tubes being tightened to steam-cham-

bers by means of flanges, firmly attached to the ends of the superheating-tubes, the front of the steam-chamber being in an upright position and directed toward the door of the smoke-box of the boiler.

5. A boiler, with superheating-tubes, arranged in some enlarged smoke-tubes of the boiler, the ends of the superheating-pipes being bent backward in such a manner that they are turned backward into the direction 75 of the tube-plate of the smoke-box, the ends of the tubes being tightened to steam-chambers by means of flanges, firmly attached to the ends of the superheating-tubes, and of fastening means lying in the middle line between the ends of the superheating-tubes, the front of the steam-chamber being in an upright position and directed toward the door of the smoke-box of the boiler.

6. A boiler, with superheating-tubes, arranged in some enlarged smoke-tubes of the boiler, the ends of the superheating-pipes being bent backward in such a manner that they are turned backward into the direction 80 of the tube-plate of the smoke-box, the single 85 superheating-tubes consisting of an outward and return steam-passage arranged in an enlarged smoke-tube of the boiler, and the ends of these tubes being tightened to steam-chambers by means of flanges firmly attached to the ends of the superheating-tubes, and of fastening-screws lying between the ends of the superheating-tubes, the front of the steam-chamber being in an upright position 90 and directed toward the door of the smoke-box of the boiler.

7. A boiler, with superheating-tubes, arranged in some enlarged smoke-tubes of the boiler, the ends of the superheating-pipes being bent backward in such a manner that 105 they are turned backward into the direction of the tube-plate of the smoke-box, the single superheating-tubes consisting of several outward and return steam-passages arranged in an enlarged smoke-tube of the boiler, and the 110 ends of these tubes being tightened to steam-chambers by means of flanges firmly attached to the ends of the superheating-tubes, and of fastening-screws lying between the ends of the superheating-tubes, the front of 115 the steam-chambers being in an upright position and directed toward the door of the smoke-box of the boiler.

8. A boiler, with superheating-tubes, arranged in some enlarged smoke-tubes of the boiler, the ends of the superheating-pipes being bent backward in such a manner that they are turned backward into the direction 120 of the tube-plate of the smoke-box, the single superheating-tubes consisting of several outward and return steam-passages arranged in 125 two enlarged smoke-tubes.

9. A boiler, with superheating-tubes, arranged in some enlarged smoke-tubes of the boiler, the ends of the superheating-pipes 130

being bent backward in such a manner that they are turned backward into the direction of the tube-plate of the smoke-box, the single superheating-tubes consisting of several outward and return steam-passages arranged in two enlarged smoke-tubes, the ends of the tubes being tightened to steam-chambers by means of flanges and of fastening-screws lying on the middle line between the ends of the superheating-tubes, the front of the steam-

chamber being in an upright position and directed toward the door of the smoke-box of the boiler.

In witness whereof I have hereunto set my hand in the presence of two witnesses.

WILHELM SCHMIDT.

Witnesses:
